METHOD AND APPARATUS FOR ANCHORING
DRAW CORDSRussell Gleave and Edwin A. Dickmann, St. Louis,
Mo., assignors to Bemis Bro. Bag Company, St.
Louis, Mo., a corporation of MissouriOriginal application December 26, 1946, Serial No.
718,308. Divided and this application October
6, 1949, Serial No. 119,914

10 Claims. (Cl. 1—1)

1

This invention relates to methods and apparatus for anchoring draw cords and more particularly to methods and apparatus for anchoring the ends of a draw cord woven into an open-mesh fabric bag.

This application is a division of our copending application entitled Draw Cord Anchorage, Serial No. 718,308, filed December 26, 1946.

The invention has as its particular object the provision of a method and apparatus for quickly, efficiently and reliably anchoring the ends of a draw cord in an open-mesh bag to prevent the draw cord from being pulled out of the bag when it is drawn up to close the mouth of the bag. In general, the method involves the immersion of the portion of the bag including the ends of the draw cord in a pool of fluid adhesive and driving a staple through the bag in the area of the pool and clinching it around the ends of the draw cord while the said portion of the bag is so immersed in the pool of adhesive. The apparatus, in general, comprises a stapler including a clincher block having a clinching recess and a staple-driving element adapted to drive a staple into the recess for clinching it, and means for supplying fluid adhesive to the surface of the clincher block. Other features will be in part apparent and in part pointed out hereinafter.

The invention accordingly comprises the elements and combinations of elements, steps and sequence of steps, features of construction and manipulation, and arrangements of parts which will be exemplified in the structures and methods hereinafter described, and the scope of the application of which will be indicated in the following claims.

In the accompanying drawings, in which one of various possible embodiments of the invention is illustrated:

Fig. 1 is a view of a completed bag embodying the improved draw cord anchorage of the invention;

Fig. 2 is an enlarged fragmentary view of the bag of Fig. 1 particularly illustrating the improved draw cord anchorage;

Fig. 3 is a side elevation of the improved apparatus of the invention for forming the draw cord anchorage of Fig. 2;

Fig. 4 is a fragmentary front elevation of the apparatus of Fig. 3;

Fig. 5 is an enlarged section taken on line 5—5 of Fig. 4;

Fig. 6 is a view diagrammatically illustrating equipment for continuous production of the draw cord anchorages of Fig. 2; and,

2

Fig. 7 is an enlarged detail section taken on line 7—7 of Fig. 6.

Similar reference characters indicate corresponding parts throughout the several views of the drawings.

Fruits, vegetables and the like are often packed in open-mesh bags, such as illustrated at 1 in Figs. 1 and 2, which have draw cords 3 for closing the mouths of the bags after filling. These bags are generally formed from lengths of open-mesh fabric, such as a leno-weave fabric, cut from a continuous web in which the draw cord is pre-woven along one margin. A bag is formed by folding such a length of fabric at 5 to bring the cut ends 7 of the length of the fabric and the cut ends 9 of the draw cord together, and then stitching the ends 7 and the bottom margins 11 to form side and bottom seams 13 and 15, respectively. This results in an open-mouthed bag having draw cord 3 loosely interwoven therein adjacent its mouth.

The ends 9 of the draw cord must be anchored to the bag to prevent the cord from being pulled out when it is drawn up to close the mouth of the bag. The stitching 13 cannot be relied upon for anchoring these ends since it is too coarse, due to the open-mesh characteristic of the bag fabric. Heretofore, the ends have been anchored either by knotting them, or by folding over the corner of the bag prior to stitching. Knotting is a tedious and time-consuming procedure. The folding procedure is more satisfactory than knotting, but is time-consuming. This invention provides an improved, secure anchorage for the ends of the draw cord which may be quickly and easily formed without any knotting, folding or the like.

As illustrated in Fig. 2, the draw cord anchorage of this invention comprises a staple 17 driven through the bag fabric and clinched around the ends of the draw cord, and a mass of adhesive 19 adhesively bonding the ends of the cord to the bag. The adhesive is applied over a substantial area surrounding the staple and not only bonds the ends of the cord to the bag but also fills or tends to fill the interstices of the open-mesh bag fabric, as indicated at 21, to form a stiff matrix in which the staple and the ends of the cord are adhesively embedded. This locally stiffens the bag weave, prevents displacement of the staple relative to the bag by preventing sliding of the staple along the individual strands of the open-mesh bag fabric around which it is clinched, and distributes the load to increase the resistance of the anchorage to pull-

ing out of the cord. The result is an anchorage wherein the ends of the cord are securely affixed to the bag to prevent the cord from being pulled out of the bag under the usual amount of force applied to the cord in drawing it up to close the bag mouth. The staple and adhesive are applied outside of the side seam 13, so as not to obstruct the bag mouth.

This invention also contemplates a novel method for quickly and efficiently forming the above-described matrix anchorage with minimum manipulation of the bag, thus effecting rapid production. In accordance with this method, the anchorage is formed by presenting the corner of the bag to a stapling apparatus, the clincher block or anvil of which is maintained covered with fluid adhesive, with the ends of the draw cord substantially centered with respect to the staple-driving element of the apparatus. The stapler is then operated to drive the staple through the bag and to clinch it around the ends of the cord. As the bag is withdrawn from the apparatus, it picks up a mass of adhesive from the clincher block, thereby embedding the staple and the ends of the cord in adhesive. When the adhesive sets, it forms the aforesaid adhesive-stiffened portion of the bag. The only manipulation required in this method is the presentation of the bag to the stapling apparatus and withdrawal of the bag after the staple has been driven. No separate step of applying the adhesive is necessary, since the adhesive is applied coincidentally with the presentation of the bag to the stapling apparatus.

Figs. 3-5 illustrate the apparatus of this invention for carrying out this method and forming the anchorage of Fig. 2. This apparatus comprises a wire stapling machine to which is added means adapting the machine for use in conveniently carrying out the method of this invention. In general, the stapling machine comprises a support including a base 25, a vertical column 27, and a horizontal head 29 extending forward from the upper end of the column. At the forward end of the head is a housing 31 enclosing the staple forming and driving instrumentalities of the machine, generally designated 33, and including a staple driving element 35. These instrumentalities are the usual ones adapted to cut off a length of wire fed thereto by feed rolls 37 from a coil 39 carried by a coil holder 41 supported on head 29, to form this length of wire into a staple of inverted U-shape, and to drive the staple through the work and against a clincher block 43. This block is carried upon the outer end of an arm 45 adjustably mounted on column 27 and has a clinching recess 47 wherein the legs of the U-shaped staple are turned in to clinch it around the work. The staple forming instrumentalities reciprocate within housing 31, being driven by a shaft 49. This shaft is driven by a motor 51 through a transmission housed within a guard 53 under control of a pedal 55. Since the specific construction of such a stapling machine is well known further detail is unnecessary.

In accordance with the invention, means is provided for supplying fluid adhesive to the upper surface of the outer end of arm 45 to cover clincher block 43 so that a bag presented to the apparatus will pick up adhesive, as previously described. This means includes a container 57 for a supply of adhesive, carried on head 29 of the stapling machine in a bracket 59 fixed to the head. A rubber tube 61 forms a conduit for gravity feed of adhesive from an outlet 63 in the lower end of container 57 to a trough 65. Trough 65 is carried

upon arm 45 by a suitable bracket 66 and conducts adhesive to the upper surface of the outer end of arm 45 and the upper surface of the clincher block. Flow of adhesive is under control of a stop cock valve 67 connected into the lower end of tube 61. Adhesive overflowing from the outer end of arm 45 is caught in a trough 69 which conducts it to an overflow receptacle 71 placed upon a platform 73 fixed on column 27.

Also in accordance with this invention, means is provided to prevent the staple driving instrumentalities of the machine from fouling with adhesive. This means comprises a pipe 75 for conducting a solvent for the particular adhesive employed, into the housing 31 to flow downward over these instrumentalities, particularly over the lower end of the staple-driving element 35, to keep them clean of adhesive. The solvent is supplied to the pipe from a drip cup 77, such as a conventional oil drip cup, supported upon an elbow 78 at the outer end of the pipe with the outlet of the cup in communication with the elbow.

An example of a suitable fluid adhesive is a solution of nitrocellulose in a suitable solvent such as acetone, acetate ester or the like. A typical solvent in the trade is "Ansol B." Others may also be used.

Container 57 is filled with such fluid adhesive and stop cock 67 is adjusted so that adhesive flows out of the container at a rate consistent with the rate at which it is picked off the outer end of arm 45 of the stapling machine in forming anchorages. The drip cup 77 is filled with the solvent and adjusted for gradual release of solvent. In other words, a pool of adhesive is maintained on the block 43. To form an anchorage, the operator places the corner of a bag on the end of arm 45, with the ends of the draw cord substantially centered over clinching recess 47, and depresses pedal 55 to form, drive and clinch the staple. As the staple is driven and clinched, that portion of the bag fabric immediately surrounding the staple is immersed in the adhesive. After the staple is driven, sufficient adhesive is forced into the interstices around the staple and spread so as to adhere to the bag around the staple and to the ends of the draw cord. This forms the aforesaid mass of adhesive for stiffening purposes when set. Any adhesive adhering to the staple-driving element 35 is dissolved in the solvent (preferably the same as that in which the nitrocellulose is dissolved) flowing out of pipe 75 from cup 77 and down over the staple forming and driving instrumentalities.

Figs. 6 and 7 illustrate a complete installation for continuous line production of anchorages employing the apparatus of Figs. 3-5. As illustrated, a plurality of the staple-and-adhesive-applying machines of this invention are disposed at positions A adjacent a conveyor belt 79. Operators at stations B take bags from tables C and present them to the machines, the bags being delivered upon trucks D. After the stapling and adhesive applying operation has been performed on a bag, the operator places it upon conveyor belt 79, by means of which the bags are conveyed through a heating chamber 81. This is formed by a hood 83 enclosing the upper reach of the belt and a heating coil 85. The solvent evaporates in the heating chamber and the adhesive sets, to complete the process. The completed bags are taken off the belt by operators at stations E and loaded on trucks F to be conveyed away.

Another feature to be noted is that the ma-

trix-forming adhesive for the staple is applied before the staple is applied. This results in plunging the open staple into the adhesive and closing it on the clincher block in the pool of adhesive, which not only causes adhesive to surround the staple but to be included interiorly of it, so that it gains a good grip on whatever it clinches. In addition, the presence of the pool of adhesive during stapling results in the descending staple-driving element squeezing and spreading the adhesive into an extended, though local, area around the staple.

A convenient feature of the invention should be noted, namely, that the continuous application of the solvent from cup 11 to the upper portions of the clinching instrumentalities results in a gravity-flow of the solvent as it does its cleaning and final appearance of the solvent in the pool of adhesive carried on the block 47. It will be clear that the amount of solvent required in the adhesive derived from the container 57 may be reduced by the amount of the solvent flowing into the pool from the cup 11. Thus under normal operating conditions the cleaning solvent supplies some of the normal proportion of solvent needed.

In view of the above, it will be seen that the several objects of the invention are achieved and other advantageous results attained.

As many changes could be made in the above methods and constructions without departing from the scope of the invention, it is intended that all matter contained in the above description or shown in the accompanying drawings shall be interpreted as illustrative and not in a limiting sense.

We claim:

1. The method of anchoring the ends of a draw cord woven into an open-mesh fabric bag adjacent its mouth, comprising the steps of immersing the portion of the bag including the ends of the cord in a pool of fluid adhesive, and driving a staple through the bag in the area of the pool and clinching it around the ends of the draw cord while said portion is so immersed in said pool of adhesive.

2. Apparatus for forming an anchorage for the ends of a draw cord woven into an open-mesh fabric bag adjacent its mouth, comprising a stapling apparatus including a clincher block having a clinching recess and a staple-driving element adapted to drive a staple into said recess for clinching it, a container for a supply of fluid adhesive and means for supplying fluid adhesive from the container to the surface of the clincher block.

3. Apparatus for forming an anchorage for the ends of a draw cord woven into an open-mesh fabric bag adjacent its mouth comprising a stapling apparatus including a clincher block having a clinching recess and a staple-driving element adapted to drive a staple into said recess for clinching it, a container for a supply of fluid adhesive, and a valve conduit leading from the container to the clincher block for continuously supplying fluid adhesive to the surface of the clincher block to maintain a pool into which successive bag portions including cord end portions are placed and into which pool successive staples are driven.

4. Apparatus for forming an anchorage for the ends of a draw cord woven into an open-mesh fabric bag adjacent its mouth comprising a stapling apparatus including a clincher block having a clinching recess and a staple-driving

element adapted to drive a staple into said recess for clinching it, and means for supplying fluid adhesive to the surface of the clincher block, and means for supplying a solvent for the adhesive to the staple-driving element to clean it of adhesive.

5. Apparatus for forming an anchorage for the ends of a draw cord woven into an open-mesh fabric bag adjacent its mouth, comprising

10 a stapling apparatus including a clincher block having a clinching recess and a staple-driving element adapted to drive a staple into said recess for clinching it, means for continuously supplying fluid adhesive to the surface of the clincher block to maintain a pool of adhesive thereon, and means for continuously supplying a solvent for the adhesive to an upper portion of the staple-driving element to flow down the same by gravity and clean it of adhesive and then to flow into the pool.

6. Apparatus for forming an anchorage for the ends of a draw cord woven into an open-mesh fabric bag, comprising a stapling apparatus including a clincher block having a

25 clinching recess and a staple-driving element adapted to drive a staple into said recess for clinching it, means for conducting fluid adhesive from a supply to flow upon the surface of the clincher block, means for controlling the 30 flow of adhesive, and means for collecting overflow of adhesive from said clincher block.

7. Apparatus for forming an anchorage for the ends of a draw cord woven into an open-mesh fabric bag, comprising a stapling apparatus including a clincher block having a

35 clinching recess and a staple-driving element adapted to drive a staple into said recess for clinching it, means for conducting fluid adhesive from a supply to flow upon the surface 40 of the clincher block, means for controlling the flow of adhesive, means for collecting overflow of adhesive from said clincher block, and means for supplying a solvent for the adhesive to the staple-driving element to clean it of adhesive.

8. Apparatus for forming an anchorage for the ends of a draw cord woven into an open-mesh fabric comprising a stapling apparatus including a clincher block having a clinching

50 recess and a staple-driving element adapted to drive a staple into said recess for clinching it, means for continuously conducting fluid adhesive from a supply to flow upon the surface of the clincher block to form a pool thereon, means for controlling the flow of adhesive, 55 means for collecting overflow of adhesive from the pool on said clincher block, means for continuously conducting a solvent for the adhesive from a supply of said solvent to flow by gravity over the staple-driving element and clean it of adhesive and to gravitate into said pool, and means for controlling the flow of solvent.

9. Apparatus for forming an anchorage for the ends of a draw cord woven into an open-mesh fabric bag, comprising a stapling apparatus including a supporting column, a head extending horizontally outward from the upper end of the column, staple forming and driving means at the outer end of said head, a clincher block carried upon the outer end of an arm extending outward from said column, said block

70 having a clinching recess wherein a staple driven by said staple-driving means is clinched, a container for fluid adhesive carried by said head, means for conducting fluid from said container 75 to flow upon the surface of said clincher block,

7

said means including a valve for controlling said flow, and means mounted on said apparatus for collecting overflow of adhesive from said clincher block.

10. Apparatus for forming an anchorage for the ends of a draw cord woven into an open-mesh fabric bag, comprising a stapling apparatus including a supporting column, a head extending horizontally outward from the upper end of the column, staple forming and driving means at the outer end of said head, a clincher block carried upon the outer end of an arm extending outward from said column, said block having a clinching recess wherein a staple driven by said staple-driving means is clinched, a con-

8

tainer for fluid adhesive carried by said head, means for conducting fluid from said container to flow upon the surface of said clincher block, said means including a valve for controlling said flow, means mounted on said apparatus for collecting overflow of adhesive from said clincher block, and means for conducting a solvent for the adhesive from a supply of said solvent to flow over the staple-driving element and clean it of adhesive.
